UNITED STATES PATENT OFFICE.

FRANK O. BROWN, OF NEW YORK, N. Y.

TUNNELING-MACHINE.

SPECIFICATION forming part of Letters Patent No. 340,759, dated April 27, 1886.

Application filed January 15, 1886. Serial No. 189,766. (No model.)

To all whom it may concern:

Be it known that I, FRANK O. BROWN, of the city, county, and State of New York, have invented a new and useful Improvement in 5 Tunneling-Machines, of which the following is a full, clear, and exact description.

Reference is to be had to the accompanying drawings, forming a part of this specification, in which similar letters of reference indicate 10 corresponding parts in both the figures.

Figure 1 is a sectional side elevation of my improved tunneling-machine. Fig. 2 is a sectional end elevation of the same, taken through the line *x x*, Fig. 1.

15 The object of this invention is to provide tunneling-machines constructed in such a manner that they can be readily forced forward through the ground, and will allow the brick-work to be readily laid.

20 The invention consists in the construction and combination of various parts of the machine, as will be hereinafter fully described.

A represents the shell or casing of the machine, which is made of plate-iron bolted together and of cylindrical or other desired shape. The shell A is made with its forward 25 end inclined or beveled, and is arranged with its longest side upward, as shown in Fig. 1.

To the shell A, at a little distance from the 30 forward end of its shortest side, is secured air-tight a transverse partition, B.

Through the center and side parts of the partition B are formed a number of man-holes, C, which are closed air tight when not in use 35 by plates D.

Through one of the man-holes C is passed a conveyer-tube, E, within which is placed a shaft, F, provided with a spiral flange, G, and which projects a little beyond the forward end of the tube E and to, nearly to, or a little beyond, the forward edge of the shell A.

In the lower side of the rear part of the tube 45 E and in the rear of the partition B is formed an opening, H, through which the earth carried back by the conveyer is discharged, and is then carried out through the completed part of the tunnel.

To the rear end of the conveyer-shaft F is attached a gear-wheel, I, of a driving mechanism, and motion is designed to be given to the said shaft from a steam-engine.

J is a steam-pipe, which passes through the

partition B, and its rear end is connected with the boiler of the engine or other steam-generator.

55

Within the rear part of the shell A is placed a short shell, K, of the same form as the said shell A, and arranged concentric therewith. The interior shell, K, is connected with the exterior shell, A, and is supported in position 60 by brackets L, attached to the shell A and to the forward part of the shell K. The shell K is made so much smaller than the shell A as to leave a space between the said shells to receive the brick-work to form the wall of the 65 tunnel.

If desired, the lower part of the interior shell can be omitted.

When the shell A is to be moved forward, the pipe E is withdrawn, and the cover of the 70 man-hole through which it passed is closed.

The steam-pipe J should be provided with a valve, and one of the man-hole covers or some part of the partition B should be provided with a valve opening outward, through 75 which air escapes when the valve in the steam-pipe J is opened. When steam begins to come out of the air-discharge valve in the valve the steam-pipe J is closed, and as the steam condenses the shell A is forced forward by atmospheric pressure. The pipe E is then inserted, and the removal of the soil is resumed.

If desired, the forward movement of the machine can be assisted by compressed air confined in the rear of and allowed to press 85 against the partition B.

In case the ground in front of the machine be too hard to be loosened and carried out by the conveyer, the upper part of the conveyer-tube can be made open, so that men can loosen 90 the ground with picks and shovel it into the said tube, when it will be carried out by the conveyer and discharged from the said tube, in the manner hereinbefore described.

Having thus fully described my invention, I 95 claim as new, and desire to secure by Letters Patent—

1. The combination, with the shell A, made of the shape and size of the required tunnel, and provided with an air-tight cross-partition, B, having man-holes C, closed by plates D, of the tube E, the flanged shaft F G, a driving mechanism and a steam-pipe, J, substantially as herein shown and described, where-

by the earth is removed in front of the machine and the machine is forced forward by air-pressure, as set forth.

2. In a tunneling-machine, the combination, with the exterior shell, A, having cross-partition B, and provided with a conveyer, E F G, of the interior shell, K, and the supporting-brackets L, connecting it with the said exterior shell, A, substantially as herein shown and described, whereby the wall of the tunnel can be laid within the rear part of the said exterior shell, as set forth.

3. The combination, with the shell A, bevelled at its forward end, and provided with an air-tight cross-partition, B, having man-holes, 15 of the interior shell, K, and the supporting-brackets L, substantially as herein shown and described.

FRANK O. BROWN.
